DISPENSING TOP FOR A PRESSURE CAN

Wallace H. Steinberg, Matawan, N.J., assignor to
Johnson & Johnson

Filed Apr. 3, 1964, Ser. No. 79,335

Term of patent 14 years

(Cl. D58—26)

Fig. 1.

Fig. 2.

Fig. 3.

Fig. 4.

FIG. 1 is a rear elevational view of the dispensing top for a pressure can showing my new design;

FIG. 2 is a side elevational view thereof;

FIG. 3 is a front elevational view thereof; and

FIG. 4 is a top plan view thereof.

I claim:

The ornamental design for a dispensing top for a pressure can, as shown.
